United States Patent Office

Des. 223,335
Patented Apr. 11, 1972

223,335

COMBINED BOTTLE AND CLOSURE THEREFOR

Robert J. Donoghue, 900 Windsor Ave.,
Windsor, Conn. 06095

Filed Oct. 22, 1970, Ser. No. 25,602

Term of patent 14 years

Int. Cl. D9—01

U.S. Cl. D9—10

FIG. 2

FIG. 1

FIG. 4

FIG. 3

FIG. 6

FIG. 5

FIG. 7

FIG. 8

FIG. 1 is a side elevational view of a combined bottle and closure therefor embodying my new design;

FIG. 2 is a top plan view thereof;

FIG. 3 is a bottom view of FIG. 1;

FIG. 4 is an end elevational view of FIG. 1;

FIG. 5 is a side elevational view, like FIG. 1, with the closure member removed;

FIG. 6 is a top plan view of FIG. 5;

FIG. 7 is an end elevational view, like FIG. 4, with the closure member removed; and

FIG. 8 is a fragmentary cross-sectional view through the eyecup portion—the section taken on line 8—8 of FIG. 6.

I claim:

The ornamental design for a combined bottle and closure therefor, substantially as shown.
